UNITED STATES PATENT OFFICE

GEORGE A. BLAKE, OF NEW BEDFORD, MASSACHUSETTS

FAUCET

Application filed June 8, 1929. Serial No. 369,494.

This invention relates to faucets, particularly to self-closing faucets of the general type shown in United States Patent No. 927,100 issued to me July 6, 1909.

5 One purpose of the invention is to provide a faucet of this class in which the valve is adapted to operate without leakage under a considerable back pressure, as for example when controlling the flow to a pipe line or 10 hose.

Other objects of the invention are to provide an improved hand operating device for the valve, to provide an improved stop mechanism for the hand operating device in which 15 the stop mechanism may be turned to a position which will hold the valve open, to provide an improved connection between the rotary operating means and the valve casing by means of which leakage along the axis 20 of the rotary operating mechanism is prevented and by means of which the rotary operating mechanism may be easily removed from the valve casing, and to provide means for releasing any accumulation of liquid from 25 the cushioning chamber, and relieving a vacuum in the cushioning chamber.

Other objects of the invention will be apparent from the following specification in which various advantageous features of the 30 improved construction are described in detail.

In self-closing valves such as shown in Patent No. 927,100 the valve stem below the valve carries a piston which is movable up and down in a rather closely fitting cylinder 35 for the purpose of cushioning the closing movement of the valve. It is not practicable to make the piston fit the cylinder closely enough to prevent leakage of liquid past the piston into the cylinder, but in the ordinary self-closing faucet there is no very great tendency for the liquid to leak past the cushioning piston since the valve discharges into the atmosphere and the pressure on the discharge side of the valve seat is relatively 40 small. However, when a valve of this type is connected to a hose or pipe line of considerable flow resistance and a back pressure is built up in the portion of the valve beyond the valve seat the tendency for liquid to leak past the cushioning piston is greatly increased.

This tendency is very undesirable since the liquid leaking into the cushioning cylinder tends to run down out of the cushioning cylinder along the projecting valve operating stem. In the improved valve construction described and illustrated in the present specification the difficulty of liquid leaking out along the operating mechanism is entirely obviated. In the improved construction the joint where the operating mechanism enters 50 the cushioning chamber is sealed automatically by the pressure within the cushioning chamber.

In addition, separate means is provided for releasing at will and in a controlled manner any accumulation of liquid in the cushioning chamber, and for automatically relieving any vacuum that is formed in the cushioning chamber during the opening of the valve.

In the accompanying drawings:

Figure 1 is a side elevation of a self-closing valve constructed in accordance with this invention;

Figure 2 is a fragmentary view of a portion of the valve shown in Fig. 1 but showing the operating handle in its upper or open position and showing the cooperating stop 25 turned to hold the operating handle in its raised position;

Figure 3 is a sectional view through the valve shown in Fig. 1;

Figure 4 is a sectional view along the line 4—4 of Fig. 3;

Figure 5 is a sectional view through a tank valve embodying the invention; and

Figure 6 is a fragmentary sectional view of a modified form of valve wherein means for limiting the movement of the valve in an opening direction is carried by the piston of the valve.

Referring particularly to Figures 1 and 3, the valve casing 1 is provided at one end with a threaded inlet connection 2, at the other end with a threaded outlet connection 3, and an interior valve seat 4 with which the valve 5 cooperates. Above the valve 5 and integral therewith is provided a valve closing piston 6 in a cylinder 7, the outer end of which is closed by a removable cap 8. In this valve, as is customary, the valve closing piston 6

fits the cylinder 7 loosely enough to allow the liquid pressure from the inlet side of the valve to operate in the cylinder 7 to urge the valve 5 toward its seat.

5 Depending from and integral with the valve 5 is provided a stem member 34 which is enlarged to form a cushioning piston 9 extending into an enclosed cushioning chamber 10. Comparing Figures 3 and 4 it will be seen that the cushioning chamber 10 has the shape, roughly, of two intersecting cylinders and comprises a vertically disposed cylindrical portion 11 in which the cushioning piston 9 may slide up and down and a horizontally disposed cylindrical extension 12 intersected by and connected with the vertically disposed portion.

10 The bottom 13 of the cushioning chamber slopes gradually downward to its lowest point 14, at which is provided a valve 15 whose construction and operation are hereinafter described.

15 As shown in Figure 4, one of the side walls of the cushioning chamber is closed by a removable threaded plug 18 provided with a hole 19 extending therethrough for the reception of a rotary arbor 20 which is pivotally supported at its opposite end in a depression 21 in the wall of the valve casing. Arbor 20, which extends outwardly through the removable threaded plug 18 is provided at its outer end with a shank 22 which is operatively engaged by the operating handle 23, by means of which the arbor 20 may be rotated.

20 Referring to Figures 3 and 4, it will be seen that the arbor 20 is provided with an integral laterally extending arm 28 which engages in a slot 29 in the cushioning piston 9 at the lower end of the stem member 34. By means of this construction the stem member 34 may be moved up and down by raising and lowering the operating handle 23, thus opening or closing the valve 5. This construction has the advantage of allowing the valve to be both positively opened and positively closed by the operating handle. In the operation of the device as a self-closing faucet, the valve is opened by raising the operating handle 23. As long as handle 23 is held up the valve will

25 remain open, but when handle 23 is released, the valve will close, due to the force of the liquid in cylinder 7 acting upon piston 6, and the weight of handle 23. The closing movement of the valve is cushioned by the compression of air in cushioning chamber 10 by piston 9. The operating handle 23 is of considerable length and hence normally exerts an effective force on the valve tending to lower and close it.

30 Referring to Figure 4, it will be seen that the hole 19 through the removable threaded plug 18 is provided with a counter-sunk portion 30. The rotary arbor 20 is provided with an enlarged shoulder 31 which extends into and closely fits the counter-sunk portion 30

in the plug 18. Between the enlarged shoulder 31 and the bottom of the counter-sunk portion 30 any suitable packing material, illustrated at 32, is provided. By means of this construction the joint between the rotary arbor 20 and the cushioning chamber is made self-sealing. Any liquid pressure built up in the cushioning chamber 10 due to leakage past the piston 9 will bear upon the enlarged shoulder 31 and force it laterally outward against the packing 32 and thus effectively seal the joint.

35 The valve 15 which is provided in the lower part of the bottom of the cushioning chamber 10 is an inwardly opening valve which is opened by the suction created in the cushioning chamber 10 as the piston 9 is moved upwardly out of the chamber when opening the main valve 5. This allows air to enter the cushioning chamber from outside of the valve 35 and allows the main valve 5 to open without the necessity of applying sufficient force to break a vacuum in the cushioning chamber. As shown in Fig. 3, the valve 15 is provided with a downwardly disposed stem 16 which extends outside of the valve casing. By pressing upwardly by hand on the stem 16 the valve 15 may be lifted and opened to drain out from the cushioning chamber 10 any accumulation of liquid which has leaked past the cushioning piston 9.

40 Referring to Fig. 1 it will be seen that an upper stop 24 is fixed rigidly to the side of the valve casing and that a lower stop 25 is eccentrically pivotally mounted on a pin 26 so that it may be swung upwardly into the position shown in Figure 2. In this position an elongated portion 27 of the stop engages the operating handle 23 to hold the latter in its upper position and thus hold the valve open. When in this upper position, as shown in Fig. 2, the lower stop 25 serves to wedge the operating handle 23 against the upper stop 24 and hold the valve open against the pressure of the liquid. Due to this wedging action, lower stop 25 will hold itself in the upper position and hold the valve open until released by hand, whereupon the pressure of the liquid upon piston 6 will close the valve.

45 It will be seen that the stop 24 constitutes a means for limiting the movement of the valve in an opening direction. In the modified form shown in Figure 6 a different means is provided for performing this function. In this modified form, stop 24 is dispensed with, and a stop 50 is mounted on the upper face of the valve closing piston, and is adapted to strike against the under face of the cap 8 to limit the movement of the valve in an opening direction. This limits the upward movement of the operating handle 23 and allows the stop 25 to be swung upwardly into wedging engagement therewith.

50 In the form of the invention shown in Fig.

5 the valve casing having a threaded inlet connection 48 and a threaded outlet connection 49, is provided with a chamber 40 above the valve similar to the upper chamber 7 of the valve casing shown in Fig. 3, said chamber being closed by a detachable cap 8 and the valve 42 being held against its seat 43 by the pressure of liquid against the piston 44 as in the valve shown in Fig. 3. The valve 10 of Fig. 5 is not provided with a cushioning piston and chamber but is provided with a depending stem 45 provided with a recess 46 for engaging the arm 28 of operating mechanism which is identical with that shown in 15 Fig. 4, and which is housed in a laterally disposed cylindrical extension 47 of the casing and closed at one side by a removable threaded plug 18 with its accompanying packing 32 identical with that shown in Fig. 4.

20 It will be seen that in the form of the invention shown in Fig. 5 the need of preventing leakage at the connection between the operating member and the valve casing is even more acute than in the form shown in 25 Fig. 3 since in the type of valve shown in Fig. 5 the operating mechanism is not contained in an enclosed chamber, in the sense that chamber 10 is enclosed, but is subjected to the full back pressure of the liquid on the 30 delivery side of the seat without the shielding influence of a cushioning piston.

Having thus described the invention, what is claimed as new and desired to be secured by Letters Patent is:

35 1. In a faucet, the combination of a valve casing, a valve seat therein, a movable valve member associated with said seat, an enclosed chamber within said valve casing and rotary means within said enclosed chamber for actuating said valve member, said rotary means extending out through a wall of said valve casing, manually operable means for said rotary means including an operating handle exterior of the valve casing, a stop in the 40 direction of opening movement of said handle, and a stop in the direction of closing movement of said operating handle, said last named stop in one position permitting the operating handle to move to closing position, 45 and said last named stop being pivoted upon the valve casing, whereby it may be swung to wedge the operating handle against the first named stop and thereby hold the valve open.

50 2. In a faucet, the combination of a valve casing, a valve seat therein, a movable valve member associated with said seat, a piston movable with said valve member, an enclosed chamber in which said piston is adapted to move, and rotary means within said enclosed chamber for actuating said valve member, said rotary means extending out through a wall of said valve casing.

55 3. In a faucet, the combination of a valve casing, a valve seat therein, a reciprocable

valve member associated with said seat, a cushioning chamber in said casing, a piston extending into said cushioning chamber and connected to and movable with said reciprocable valve member, rotary means in said cushioning chamber for actuating said valve member, said rotary means extending out of said cushioning chamber through a wall of said valve casing and means actuated by pressure within the cushioning chamber for preventing leakage out of the cushioning chamber between said rotary means and the valve casing.

4. In a faucet, the combination of a valve casing, a valve seat therein, a reciprocable valve member associated with said seat, a cushioning chamber in said casing, a piston extending into said cushioning chamber and connected to and movable with said reciprocable valve member, rotary means in said cushioning chamber for actuating said valve member, said rotary means extending out of said cushioning chamber through a wall of said valve casing and means, including a shoulder carried by said rotary means within said cushioning chamber and adapted to be forced outwardly against said valve casing by fluid pressure, for preventing leakage out of the cushioning chamber between said rotary means and the valve casing.

5. In a faucet, the combination of a valve casing, a valve seat therein, a movable valve member associated with said seat, an enclosed chamber below said seat, a piston extending into said chamber and connected to and movable with said valve member, rotary valve operating means in said chamber and a suction operated valve operable by suction within said chamber to admit air thereto.

6. In a faucet, the combination of a valve casing, a valve seat therein, a movable valve member associated with said seat, an enclosing chamber below said seat, a piston extending into said chamber and connected to and movable with said valve member, rotary valve operating means in said chamber, a suction operated valve operable by suction within said chamber to admit air thereto and means for manually opening said suction operated valve whereby an accumulation of fluid in the enclosed chamber may be drained.

7. In a faucet, the combination of a valve casing, a valve seat therein, a reciprocable valve member associated with said seat, an enclosed chamber, a piston extending into said enclosed chamber and connected to and movable with said reciprocable valve member and a manually operable valve for draining an accumulation of fluid from the enclosed chamber.

8. In a faucet, the combination of a valve casing, a valve seat therein, a valve associated with said seat, an inlet chamber and an outlet chamber in said casing disposed upon opposite sides of said valve seat, another
